[57] CLAIM

The ornamental design of a foam pad for feeding and polishing plant leaves, as shown and described.

DESCRIPTION

FIG. 1 is a top perspective view of a foam pad for feeding and polishing plant leaves showing our new design;

FIG. 2 is a side elevational view thereof, the opposite side being substantially similar in appearance;

FIG. 3 is a top plan view thereof;

FIG. 4 is a bottom plan view thereof;

FIG. 5 is a front elevational view thereof; and

FIG. 6 is a rear elevational view thereof.

FIG. 1

FIG. 2

FIG. 3

FIG. 5

FIG. 6
